METHOD AND APPARATUS FOR SWEATING
WAXESFred Hederhorst, Baytown, Tex., assignor to
Standard Oil Development Company, a corpora-
tion of Delaware

Application December 26, 1941, Serial No. 424,414

18 Claims. (Cl. 196—20)

The present invention relates to improvements in the art of refining petroleum wax and in particular it relates to improvements in a continuous process for "sweating" crude wax recovered customarily by refrigerating, and centrifuging, settling or filtering.

Prior to my invention, the conventional method for producing a finished wax from a crude wax by the so-called sweating process involved melting the wax and discharging it into sweating pans where it was solidified and supported on perforated plates or screens. The pans were first filled with water to levels just above the screens and the unsweated wax was run in and floated upon the water so that, after cooling and withdrawing the water, the solidified wax rested upon the screens. Heated air was then circulated over the pans and, as the sweating of the wax began, the temperature of the heated air was slowly increased so that the temperature of the wax increased gradually, and increasingly higher melting fractions of the wax slowly melted, flowed through the remaining crystals of wax, and dropped through the supporting screens into the pans from whence the molten fractions, or "foots oil," were withdrawn. The temperature of the pans was ultimately held at a temperature slightly below that of the desired melting point of the wax for a time period of from 5 to 20 hours to provide ample opportunity for the "foots oil" to run out of the resulting "crude scale" or crystalline wax. The sweated wax was then melted by further raising the temperature and was run off for storage or further treatment. Approximately 25 to 72 hours were required to complete the sweating cycle, actual sweating time being about 65% of the total. The process above described is of the intermittent type, obviously, and is a very time-consuming operation.

Speaking generally at first, my invention relates to a continuous method for sweating wax and, in its essence, involves rotating a cylindrical filter slightly immersed in a pan of the crude molten wax, whereupon a layer of the molten wax is deposited on the outer surface of the cylinder and, as the filter rotates, the layer of wax is gradually heated to a maximum temperature, during which time the oil and lower melting point waxes flow through the crystalline wax toward the axis of the rotating drum, the flow of wax being aided by suction or pressure, and finally the "foots oil" and low melting point wax are withdrawn from the system. However, an important feature of my invention in-

volves applying heat to the layer of wax undergoing sweating on the surface of the drum by circulating a heating medium in close proximity to the wax, the circulation of the heating fluid being controlled by the operation of a master valve, axially disposed on the end of the drum. However, an important feature of my invention resides in the concept of heating or cooling the layer of wax deposited on the drum 10 as desired, all of which will more fully appear hereinafter.

My invention will be best understood by reference to the accompanying drawings which show diagrammatically a suitable apparatus in 15 which my invention may be carried into effect.

Fig. 1 is a side view of my improved sweating apparatus shown in position in a pan containing molten wax to be sweated;

Fig. 2 is an end view of the drum (across sections II—II, Fig. 1) illustrating the product discharge flow, the drum being in position in a pan containing molten wax;

Fig. 3 is also an end view of the drum (across sections III—III, Fig. 1) illustrating the temperature control during the cooling and heating cycles of the sweating operation;

Fig. 4 is the rotatable portion of a master valve disposed at one end of the drum concentrically with respect to the axis thereof;

Fig. 4A is the stationary portion of the master valve corresponding to the rotatable portion shown in Fig. 4;

Fig. 5 is the rotatable portion of a master valve which is disposed at the opposite end of the drum from the first mentioned master valve, and is also concentrically disposed with respect to the axis thereof; and

Fig. 5A is a stationary portion of the valve corresponding to that shown in Fig. 5.

Similar reference characters refer to similar parts throughout the several views.

Referring in detail to the drawings, I represents a cylindrical drum supported by suitable standards 2 and immersing, as shown, into a feed bowl 3 containing a quantity of crude molten wax 4. The drum is rotated by any suitable driving means, not shown, such as an electric motor. Peripherally disposed along the entire length of the drum a coil of pipe 10 is provided to conduct a heating or cooling fluid in close proximity to the outer surface of the drum. The coil of pipe is supported on a foraminous member, such as a screen 12, or preferably, as shown more fully in Fig. 2, a honeycombed grill. 55 Finned tubes or any other suitable arrangement

to provide maximum heat distribution may also be used. As shown in the drawings, the screen or grill work is spaced apart from the outer surface of the drum proper, forming an annular space 14. (See Fig. 1.)

Referring in particular to Fig. 2 in the modification which I have chosen to illustrate my invention, the drum is internally divided into 12 sectors, S, by spaced radially disposed plates 5. It will be understood, however, that a greater or lesser number of such sectors may be employed. The annular space between the screen or grill work and the surface of the drum is in communication in each sector through a pipe 17 with the rotating part of a master valve 20, so that, as will presently appear, "foots oil" may be withdrawn from the annular space 14 through said pipe 17, thence through the master valve 20, and rejected from the sweating device, while finished wax may be similarly withdrawn through a pipe in communication with the said master valve. In order to explain this operation more fully, reference is again had to Fig. 2 where I have shown the drum 1 immersed in the molten wax 4. The immersed portion of the drum acquires a layer of molten wax, approximately an inch in thickness. This wax is deposited on tubes or grill work in the area represented in the drawings by A by virtue of the chilling and solidifying action of a cooling medium, circulating in tubes 10. The water circulating in the tubes may be of a temperature of about 80° F., and ordinarily this will produce a layer of wax approximately one inch thick. The solidified wax then emerges from the molten wax and passes through the region represented by B in Fig. 2. During this phase of the operation, the wax is neither heated nor cooled, but in the third phase, that is, the phase represented by C, the wax is gradually heated by means of warm water at a temperature from about 90° F. to about 140° F. During this heating operation, the "foots oil" and lower melting point wax fractions are withdrawn from the higher-melting wax toward the center of the drum, first passing into annular space 14 and thence through one of the pipes 17, depending upon the particular position of the wax as it moves through this phase. When a port 25 of the rotatable portion of the master valve (see Fig. 5) is in registry with port 27 of the non-rotatable portion of the master valve, the "foots oil" or low melting point wax fraction is withdrawn through its corresponding pipe 17 and discharged from the system through said port 27.

Referring again to Fig. 2, when the time arrives that a portion of wax has reached the point D, the sweating and removal of the undesirable portions of the crude wax has been substantially completed. In order to aid in the flow of "foots oil," or low melting point wax, from the crystalline wax, vacuum may be applied at port 27 (see Fig. 5) or the drum may be enclosed in a closed shell, of somewhat larger internal diameter than the drum, and pressure may be applied by pumping a gas into the annular space between the surrounding shell and the drum. A combination of both expedients may be employed. The pressure drop across the layer of wax may vary from 1 to 50 #/sq. in., preferably from about 2 to 5 #/sq. in.

The purified crystalline wax then passes through the phase represented by D. During the passage of the cake through the phase D, the pipe 17 is out of communication with a port in a

stationary portion of the master valve. Thereafter, the cake passes into the phase represented by E, where it is again heated, preferably by circulating very hot water or steam through pipes

10, the degree of heat supplied depending upon the melting point of the wax, since in this phase the wax is melted. Simultaneously the molten wax discharges from the system through port 28 when drain pipes 17 and their corresponding ports 25 in the rotatable portion of the master valve come into registry with port 28 of the non-rotatable portion of the master valve. The last phase of the operation is represented by F on the drawings (Fig. 2) and, as in the case of phases 15 D and B, the pipe 17 and its corresponding port in the rotatable portion of the master valve is out of registry or communication with the port in the non-rotatable portion of the master valve. The same is true with respect to the phase represented by A, where the drum acquires the aforementioned layer of crude wax to be sweated.

I shall now describe the method of circulating the heating or cooling medium through pipes 10 previously referred to. The circulation of these heating or cooling media through the pipes is controlled by the master valve shown in Figs. 4 and 4A. As previously indicated, the portion of the valve shown in Fig. 4 is the rotatable portion, and it will be noted that there are 24 ports in this portion, as compared with 12 in the corresponding valve portion (Fig. 5) controlling the flow of "foots oil" and wax from the system. During the period when the wax is being picked up, that is, during the phase A (Fig. 3) cold water is introduced from some outside source, not shown, into inlet port 35 of the stationary portion of the control valve, circulates through pipes 18 to tubes 10, and is withdrawn through pipes 19 in communication with outlet port 36 of the stationary portion of the control valve. During the phase B (Fig. 3), the cooling tubes 10 are out of communication with an outside source of fluid. During the phase C, where, as previously described, the wax was heated up to a temperature of about 140° F. and the heating is effected by introducing hot water, heated at least to a temperature of 140° F., through port 50 in the stationary part of the control valve, thence through pipe 18, thence through tubes 10, thence to pipe 19, thence into port 51 in the stationary portion of the master valve, thence through pipe 52 into port 55, thence through pipe 18-A to coil 10-A, thence through coil 10-A to pipe 19-A, to port 56 in the non-rotatable portion of the master valve, thence through pipe 58 to port 60 in the said non-rotatable portion, thence through pipe 18-B, thence to coil 10-B, thence through pipe 19-B to port 65. In like manner, the hot water is introduced through port 66, circulates through pipe 18-C, coil 10-C, pipe 19-C, and is withdrawn from the system through port 67. During the phase D, the coil 10 is out of communication with any outside source of fluid. In phase E, the wax, as previously described, is melted and withdrawn from the system through port 28 (see Fig. 5). The steam necessary to melt the wax is introduced into the system through port 70 and is withdrawn through port 72, steam circulating through the coil 10 and the communicating pipes being entirely analogous to that already described in connection with the circulation of the water in phase A.

In phase F, the coil 10 is out of communication with an outside fluid.

75 I have found that best results are obtained by

rotating drum 1 at a speed of from $\frac{1}{2}$ to 4 revolutions per hour. With respect to the thickness of the layer of wax deposited on the drum in phase A, I have found that good results are obtained by so manipulating the process that the wax layer is from about $\frac{1}{2}$ to 2 inches thick. Furthermore, I have found that good sweating temperatures lie in the range of about 90 to 140° F. A convenient and economical size of the drum is one which has a diameter of about 8 ft. and a length of about 15 ft.

Many modifications of my invention may be made by those skilled in the art. In the modification which I have chosen to illustrate, it will be noted that I have shown two sections employed in the chilling of the molten wax in feed bowl 3, four sections employed in sweating the wax, and three sections employed in melting the wax. I may vary the number of sections thus employed in any of the foregoing operations, responsive to the melting point of the charge and the quality of the desired product.

The present invention having been thus described and illustrated, what is claimed as new and useful and is desired to be secured by Letters Patent is:

1. A continuous process for sweating wax which comprises depositing a film of crude wax on a rotating surface, gradually heating the wax, withdrawing "foots oil" and low melting point waxes by maintaining a pressure differential across the wax layer, and recovering the residual wax of improved quality from said rotating surface.

2. An improved process for obtaining crystalline wax of improved quality from crude wax, which comprises melting the crude wax, continuously depositing a layer of said wax on a rotating surface, heating said wax at a temperature within the range of from about 90 to 140° F., withdrawing "foots oil" and low melting point wax fractions from the crude wax by gravity, supplemented by maintaining a pressure differential across the wax layer, and thereafter recovering the residual crystalline wax of improved quality from said rotating surface.

3. The process set forth in claim 2 in which the pressure differential maintained across the wax layer during the withdrawal of the "foots oil" and low melting point wax fractions is from about 1 to 50 #/sq.in.

4. The process set forth in claim 2 in which, during the heating operation, the wax is in intimate indirect heat exchange relationship with a heating fluid.

5. An improved method for sweating slack wax to facilitate the removal of "foots oil" and low melting point wax fractions and to obtain a crystalline wax of improved quality, which comprises providing a body of molten crude wax in a feed zone, causing an enlarged drum to rotate in contacting relationship with the molten wax in such a manner that a portion of the drum is continuously submerged in the molten wax, causing a cooling fluid to flow through that portion of the drum in contacting relationship with the molten wax to chill a portion of said wax below its melting point and deposit a layer of said wax on the outer surface of said drum, causing a heating fluid to flow in close proximity to the layer of wax deposited on the drum over an area removed from the immersed portion of said drum to facilitate liberation of liquid and low boiling fractions contained within the crude wax, withdrawing the said liberated fractions from the crude wax by

wax by gravity, supplemented by the application of vacuum across the layer of heated wax, thereafter further heating the wax from which the normally liquid and low melting point fractions have been removed in order to liquefy said last named wax, and recovering said last named wax as a purified product in liquid form.

6. The process set forth in claim 5 in which the drum is rotated at a velocity of from about $\frac{1}{2}$ to 4 revolutions per hour.

7. The process set forth in claim 5 in which, during the removal of normally liquid and low melting point waxes, the crude wax is progressively heated to a temperature of about 140° F.

8. A device of the character described comprising, in combination, an enlarged, substantially cylindrical drum having closure members at both ends thereof, said drum having a foraminous curved surface, an axially disposed drive shaft projecting beyond the ends of said drum, a plurality of radially disposed spaced plates forming a plurality of non-intercommunicating chambers within said drum, a master valve disposed on said shaft, a pipe connecting the foraminous surface of said drum with said master valve, a second master valve disposed on the shaft at the end of the drum opposite that at which the first named master valve is disposed, conduit pipes disposed peripherally about the foraminous surface of said drum, pipes in communication with said peripherally disposed pipes and said second named master valve adapted to conduct a liquid from outside the drum to the peripherally disposed pipes, and means for causing rotation of said drum.

9. The apparatus set forth in claim 8 in which the foraminous surface of the drum comprises a honeycombed grillwork in which peripherally disposed finned tubes are imbedded.

10. An improved method for sweating slack wax to facilitate the removal of "foots oil" and low melting point wax fractions and to obtain a crystalline wax of improved quality, which comprises providing a body of molten crude wax in a feed zone, causing an enlarged drum to rotate in contacting relationship with the molten wax in such a manner that a portion of the drum is continuously submerged in the molten wax, causing a cooling fluid to flow through that portion of the drum in contacting relationship with the molten wax to chill a portion of said wax below its melting point and deposit a layer of said wax on the outer surface of said drum, causing a heating fluid to flow in close proximity to the layer of wax deposited on the drum over an area removed from the immersed portion of said drum to facilitate liberation of liquid and low boiling fractions contained within the crude wax, withdrawing the said liberated fractions from the crude wax by gravity, supplemented by the application of pressure across the layer of heated wax, thereafter further heating the wax from which the normally liquid and low melting point fractions have been removed in order to liquefy said last named wax, and recovering said last named wax as a purified product in liquid form.

11. A method for sweating slack wax to facilitate the removal of "foots oil" and low melting point wax fractions and to obtain a crystalline wax of improved quality, which comprises establishing a pool of slack wax in molten condition, continuously passing through said pool a body having a surface cooled to a temperature substantially below the temperature of the pool to thereby form a layer of wax on said surface, con-

tinuously moving said deposited layer of wax out of said pool, applying heat to said surface gradually after the removal of said wax from said pool, establishing a pressure gradient across said layer of wax to force out of it any "foots oil" and low melting point wax liquefied by said heat and subsequently removing the layer of sweated wax from said surface.

12. An apparatus for the sweating of slack wax, comprising a receptacle adapted to hold a pool of molten slack wax, a body adapted to move through said receptacle in such a manner as to be at least partially immersed in said pool of wax, means for moving said body through said receptacle, means for cooling at least that portion of the surface of said body arranged to be immersed in the pool of slack wax while said surface is passing through said receptacle and means for heating said surface after it has emerged from said receptacle.

13. An apparatus for the sweating of slack wax which comprises a rotating body, means arranged on the periphery of said body for receiving a layer of slack wax and disposing said layer of wax so that it has an inner surface and an outer surface, means for establishing a pressure differential across said layer of wax and means for applying heat to said layer of wax.

14. An apparatus for the sweating of slack wax comprising a rotatable body, a plurality of receptacles formed on the periphery of said body, means arranged peripherally on said body for supporting a layer of slack wax in fluid communication with said receptacles in such a manner as to provide an inner surface and an outer surface on said layer of wax, means for establishing a pressure differential across said layer of wax, means for applying heat to said layer of wax and means for withdrawing fluid from said receptacles.

15. An apparatus for the sweating of slack wax comprising a receptacle adapted to hold a pool of molten slack wax, a framework composed of hollow tubes arranged in the form of a grill mounted for movement through the pool of wax in said receptacle, means for moving said frame-

work through said pool, means for supplying a cooling medium to said tubes while they are passing through said pool of slack wax and means for replacing said cooling medium by a heating medium after said tubes have emerged from said pool of slack wax.

16. An apparatus for the sweating of slack wax comprising a receptacle adapted to hold a pool of molten slack wax, a rotatable body mounted for partial immersion in said pool of slack wax, a grill work of hollow tubes arranged peripherally on said body, means for rotating said body, means for supplying a cooling fluid to said tubular members while they are immersed in said wax, means for automatically replacing said cooling fluid by a heating fluid after said tubular members emerge from said pool of slack wax and means for continuously removing wax from said tubular members.

17. An apparatus for continuously sweating slack wax comprising a receptacle adapted to hold a pool of molten slack wax, a rotatable body mounted for partial immersion in said pool, means for rotating said body continuously, a plurality of receptacles arranged on the periphery of said body, a grill work of tubular members arranged peripherally on said body and overlying said receptacles, means for continuously drawing off fluid from said receptacles, means for supplying fluids of different temperature to said tubular members, and means for controlling the type of fluid supplied such that a cooling fluid is supplied to said tubular members while they are immersed in said pool of slack wax, heating fluid of gradually increasing temperature is supplied to said tubular members shortly after they emerge from said pool of slack wax and thereafter hotter heating fluid capable of melting sweated wax is supplied to said tubular members.

18. An apparatus according to claim 17 in which said tubular members are provided with fluid conducting inlet tubes and means are provided for connecting the latter successively with a source of cooling fluid and in order with sources of successively hotter heating fluids.

FRED HEDERHORST.
